UNITED STATES PATENT OFFICE.

BENJAMIN C. BROWN, OF CRESTON, IOWA.

DESIGN FOR A SHACKLE-BOLT LINK.

SPECIFICATION forming part of Design No. 28,541, dated May 3, 1898.

Application filed October 27, 1897. Serial No. 656,586. Term of patent 7 years.

To all whom it may concern:

Be it known that I, BENJAMIN C. BROWN, a citizen of the United States, residing at Creston, in the county of Union and State of Iowa, 5 have invented and produced a new and original Design for Shackle-Bolt Links, of which the following is a specification, reference being had therein to the accompanying drawings.

The peculiar features of this shackle-bolt 10 link are shown in the accompanying drawings, in which like reference-letters indicate corresponding parts.

Figure 1 represents a face view of the link, and Fig. 2 an edge view of the same.

15 This link is a flat plate-piece having a slot F lengthwise in the same and a notch f inter-

mediate in the side thereof, as shown in Fig. 1. The slot and notch are substantially the same size. The width of the link is in proportion to the length of the link—as about one 20 to two and a half.

Having thus fully described my invention, what I claim as new, and desire to secure by Letters Patent, is—

The design for a shackle-bolt link, substantially as shown. 25

In testimony whereof I affix my signature in presence of two witnesses.

BENJAMIN C. BROWN.
